[57] CLAIM

The ornamental design for an internal combustion engine
starter casing, as shown and described.

DESCRIPTION

FIG. 1 is a front elevational view of the casing for an internal
combustion engine starter, showing our new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a rear elevational view thereof; and,

FIG. 7 is a cross-sectional view taken along line 7—7 of
FIG. 1.
